UNITED STATES PATENT OFFICE.

DAN SEMAN, OF NEW YORK, N. Y.

LIPSTICK.

Application filed May 2, 1924. Serial No. 710,683.

This invention relates to lipsticks, and more particularly to an arrangement wherein by the full color and the delicate form of a cupid's bow can be obtained.

As is well known the present vogue of applying a lipstick of rouge or coloring material has for its purpose to give to the lips their conspicuousness, warmth of appearance and attractiveness. Pronounced appearance 10 of diminutive size and rosebud effect thereof are produced by the correct portrayal of the form of the lips in the shape of a cupid's bow.

It is the general practice among women 15 to employ a lipstick for its intended purposes by starting the lipstick from a point centrally of the upper lip and coloring the lip from this point, first in one direction and then in the other to obtain as far as possible, 20 a rough outline of a cupid's bow, which outline is then finished and made symmetrical as far as possible by removing as by a handkerchief, portions of the coating so as to give thereto the predetermined outlines. 25 As a result of this not only is the use of the lipstick time consuming, but additionally the character of the cupid's bow which is dependent both from the standpoint of its outline and its symmetrical character upon the 30 skill and patience of the one applying the lipstick.

One of the objects of my invention therefore is the provision of a lipstick wherein a lip may be coated to simulate a cupid's bow which will be of the character desired 35 and wherein this coating may be quickly and without calling upon the skill or patience of the user or without requiring any considerable length of time.

A further object of my invention is the provision of a lipstick which will automatically locate the division or lobe portions of the cupid's bow symmetrically on the lip so that on the further manipulation of the lip 40 stick the desired contours will be positioned symmetrically of the lip. This I procure by providing a marking element or lipstick of such shape that a mere imprint thereof will give upon the lip by a single contact 45 or slight manipulation thereof the form of the lipstick itself and obtain the cupid-bow form.

For the attainment of these objects and such other objects as will appear or be 50 pointed out hereinafter, I have illustrated 55 the embodiment of my invention wherein—

Fig. 1 shows in perspective, by means of a reflection in a mirror the effect produced upon a lip by my improved lipstick.

Fig. 2 is a front elevational view of the 60 lipstick and container therefor.

Fig. 3 is a view similar to Fig. 2, taken at right angles thereto.

Fig. 4 is a horizontal section taken on line 4—4 of Fig. 2. 65

Fig. 5 is a perspective view of the molded lipstick element.

In Figure 1 of the drawing I have illustrated by means of a reflection in a mirror the manner in which women at present apply 70 lipstick so as to obtain on the upper lip a coating, preferably colored, which simulates what is known as a cupid's bow, and my invention is intended to provide a lipstick which facilitates the production of a 75 cupid's bow as referred to, which on the one hand will approach the idea and which on the other hand can be formed quickly.

Upon viewing the figures of the drawing, it will be observed that I employ a lipstick 80 10 which has its side walls made partly in a form that gives the outline of a cupid's bow and this I do by providing in the lipstick two curved surfaces 11 and 12, to which I will apply the term lobes, separated 85 by the cleft 13. The dimensions and the curvatures of the lobes 11 and 12 and the character of the cleft 13 are such that when the lipstick is applied to the lip the cleft portion 13 is positioned centrally of the upper lip 90 and upon a downward movement of the lipstick 10, the upper lip will be coated either to simulate a cupid's bow or will have the beginning of such simulation. Repeated strokes of the lipstick along the lines indicated will serve to cause the coating or imprints to have a lighter or deeper tint as desired. To complete the wing portion of the cupid's bow the lipstick is then manipulated 95 in opposite directions from the center 100 so as to give the complete simulation of the cupid's bow as shown in Figure 1.

While the lipstick thus far described has been so described in this specification and has been illustrated in the drawings and given the simulation of a cupid's bow, it will be understood that the broad idea disclosed resides in giving the lipstick a predetermined cross-sectional contour so as to cause the lipstick when applied to the lip to 110 coat predetermined areas and that the cupid's bow illustrated and disclosed herein—

is merely intended to be illustrative as one character of coated contour which it may be desired to form on the lip.

The lipstick 10 as described is preferably supported in a container 15 for a sliding movement therein the lipstick being carried on the support 16 movable longitudinally along the container 15 by means of the handle member 17 mounted to slide along the slot 18 of the container. I preferably form the container 15 with curved portions 19 and 20 which conform substantially to the lobes 11 and 12 and are intended to receive the lobes therewithin, these portions 19 and 20 being separated by the depressed portion 21 of the container arranged to be received in and cooperate with the cleft portion 13 of the lipstick 10.

The depressed portion 21 may be formed in a container only for a sufficient distance below the top to enable this portion 21 to perform its intended function or if desired this depression 21 may be formed in the container for its full length.

While I have illustrated in the drawing an association between a specific character of lipstick and a specific character of holder, it will be understood that the lipstick 10 may be employed in connection with any type of holder within which it is received for free movement or on the other hand the container can be employed with a semi-plastic mass which as it is ejected from the holder that has the depression 21 therein, will be caused to have its extruded part shaped in accordance with the holder of it.

The provision of a lipstick with lobe portions 11 and 12 and the cleft 13 permits of the additional advantage that by merely pressing the lipstick upon the lip with the cleft positioned centrally of the lip as described there will be formed upon the lip a

double mark which will define the portions of the cupid's bow which it is desired to form and as a result of which a cupid's bow can thereafter be completed which will be positioned symmetrically of the lip.

The diagonally cut face as indicated at 14 may be varied in angle to suit the particular user in which case shaving down to an acute angle at the lobe portion will give highly curved lobes to the cupid bow. A less acute angle will give less curvature or flatter lobes to the cupid's bow. It will, therefore, be seen that any desired type of cupid's bow may be formed.

Having thus described my invention and illustrated its use, what I claim as new and desire to secure by Letters Patent is—

1. A lipstick comprising a coating element, said coating element being depressed centrally of the length thereof to form two lobes whereby an imprint will be formed thereby which is in the form of a cupid bow.

2. A lipstick comprising a coating mass depressed longitudinally thereof so that an imprint thereof will give a double mark upon the lip when the mass is applied thereto.

3. A lipstick comprising a coating mass and a holder therefor, said mass having a portion thereof along its length simulating a cupid's bow in cross section, the holder having an opening which corresponds in outline to the aforementioned cross section.

4. A holder for a lipstick having a discharge opening which includes a cupid bow in its outline, whereby a mass discharged through said opening will necessarily be similarly shaped.

In witness whereof, I have hereunto signed my name.

DAN SEMAN.
